REMOTE SIGNALING SYSTEM

Leo D. White, Schenectady, N. Y., assignor to
 General Electric Company, a corporation of
 New York

Application October 28, 1941, Serial No. 416,841

5 Claims. (Cl. 177—353)

My invention relates to remote signaling systems and particularly to signaling stations in which a voltage of a predetermined polarity, corresponding to the position of a remote two-position device, is impressed across an electric circuit. Heretofore, in such remote signaling systems, it has been the practice to have the signaling currents of opposite polarity control a two-position polarized relay of the type which remains in the last operating position to which it is operated until it is energized by a current of the opposite polarity and to have the polarized relay selectively control the lighting of a group of electric lamps. Such an arrangement has the undesirable feature that if for any reason a polarized relay becomes stuck in either of its two operated positions or its coil becomes open-circuited, the relay remains in the last position to which it was operated, and there is nothing to indicate whether or not the position of the polarized relay and the signaling lamps controlled thereby correctly indicate the position of the corresponding remote device.

One object of my invention is to provide an improved arrangement of apparatus whereby the signaling lamps are more positively controlled to correctly indicate the position of the corresponding remote device.

Another object of my invention is to provide an improved arrangement of apparatus whereby no signaling lamps are lighted unless the signaling current is successful in effecting the energization of a signaling relay each time the signaling current is transmitted.

My invention will be better understood from the following description when taken in connection with the accompanying drawing, the single figure of which diagrammatically illustrates a remote signaling system embodying my invention and the scope of my invention will be pointed out in the appended claims.

Referring to the drawing, RS represents a station where a plurality of two-position devices 1 are located, the positions of which are to be indicated at a dispatcher's office DO. In order to simplify the disclosure, only a single two-position device 1 is illustrated in the drawing, and this is shown as an overcurrent circuit breaker of the latched-closed type, having a trip coil 2 connected in series relation with an electric circuit 3 so that the circuit breaker 1 is opened when the current in the circuit 3 exceeds a predetermined value. The circuit breaker 1 is provided with the auxiliary contacts 4, which are closed when the main contacts of the circuit breaker are closed and with

the auxiliary contacts 5, which are closed when the main contacts of the circuit breaker are open.

In the particular arrangement shown in the drawing, two line conductors, L1 and L2, interconnect the remote station RS and the dispatcher's office DO. At the remote station, a multiple position selector switch A1 of a synchronous selected type of supervisory system is provided, which, when in a predetermined position, connects the neutral terminal of a battery B1 to the line conductors L2, and depending upon the position of the circuit breaker 1, either the positive or the negative terminal of the battery B1 is connected to the line conductor L1. Therefore, each time the selector switch A1 is in its predetermined position corresponding to the circuit breaker 1, a voltage of a predetermined polarity corresponding to the position of the circuit breaker 1 is impressed across the line conductors L1 and L2.

At the dispatcher's office DO, a multiple position selector switch A of the same type as switch A1 is provided. While the selector switches A and A1 are shown as rotary switches, it will be obvious to one skilled in the art that they may be of any other suitable type, examples of which are well known in the art and may be synchronously operated in any well-known manner. Since the details of the particular means for synchronously operating the switches A and A1 form no part of my present invention and are well known in the art, they have been omitted from the drawing in order to simplify the disclosure.

As shown, the selector switch A includes two banks of contacts, a and c, the corresponding movable wipers of which are respectively connected to the line conductor L1 through the half wave rectifiers 6 and 7, and a third bank of contacts b, the corresponding movable wiper of which is connected to the line conductor L2. The half wave rectifiers 6 and 7 are so arranged that current can flow through the movable wiper of bank a only when the negative terminal of the battery B1 is connected to the line conductor L1, and current can flow through the movable wiper of the bank c only when the positive terminal of the battery B1 is connected to the line conductor L1.

The operating winding R1 of a relay R1 is connected between the line conductor L2 and the contact of bank a of switch A corresponding to the contact of bank a1 of switch A1 to which the auxiliary contacts 4 and 5 of circuit breaker 1 are connected. The operating winding G1 of a relay G1 is connected between the line conductor L2 and a similar contact of bank c of switch A. The

relays R_1 and G_1 are provided with holding windings R_2 and G_2 respectively. When the relay R_1 is in its energized position, its contacts 9 connect the holding winding R_2 and a suitable impedance, such as a resistor 10, in series across a suitable source of current, such as the battery B. Similarly, when the relay G_1 is in its energized position, its contacts 11 connect the holding winding G_2 and the resistor 10 in series across a part of the battery B. The mid-point of battery B is so connected to the movable wiper of the bank b of the switch A that a low resistance shunt circuit is completed around the holding winding of either of the relays, G_1 or R_1 , that may be in its energized position at the time the shunt circuit is completed.

The position of the circuit breaker 1 is indicated at the dispatcher's office by the manner in which the lamps R, G, and W are lighted. The red lamp R when lighted indicates that the circuit breaker 1 is closed. The green lamp G when lighted indicates that the circuit breaker 1 is open, and the white lamp W when lighted indicates that the position of the circuit breaker 1 does not agree with the position of a two-position manually operated disagreement key DK located at the dispatcher's office.

The operation of the arrangement shown in the drawing is as follows: As long as the circuit breaker 1 remains closed and the disagreement key DK is in the position in which it is shown, the various control devices, except the selector switches A and A_1 , remain in the positions in which they are shown in the drawing. At the remote station RS, the auxiliary contacts 4 of the circuit breaker 1 are closed so that during each revolution of the movable wipers of the switch A_1 the negative terminal of the battery B_1 is connected to the line conductor L_1 and the neutral terminal of the battery B_1 is connected to the line conductor L_2 each time the switch A is in its position corresponding to the circuit breaker 1. Consequently, a current of a predetermined polarity flows through the line conductors L_1 and L_2 as long as the circuit breaker 1 remains closed.

At the dispatcher's office DO, an energizing circuit is completed across the battery B and the holding winding R_2 of the relay R_1 . This circuit also includes the resistor 10 and the contacts 9 of the relay R_1 . The red lamp R is also lighted since a circuit is completed therefor across the battery B through the contacts 12 of the energized relay R_1 .

Each time the synchronous selector switches A and A_1 simultaneously occupy the positions corresponding to the circuit breaker 1, the holding winding R_2 is deenergized since a shunt circuit is completed around this winding by the movable wiper of the bank b of switch A. The relay R_1 , however, remains in its energized position since the signaling current which is then being transmitted is in a direction to flow through the half wave rectifier 6 and energizes the operating winding R_1 . Therefore, as long as the circuit breaker 1 remains closed, the relay R_1 remains energized, and the red lamp R remains lighted.

It will now be assumed that the circuit breaker 1 operates so that its auxiliary contacts 4 are opened and its auxiliary contacts 5 are closed, thereby causing the positive terminal of the battery B_1 to be connected to the line conductor L_1 whenever the selector switches A and A_1 occupy their respective positions corresponding to the circuit breaker 1. Under such conditions, the re-

lay R_1 becomes deenergized and moves to its deenergized position and extinguishes the red lamp R. Since, however, the signaling current is in a direction to flow through the half wave rectifier 6, the operating winding G_1 of the relay G_1 is energized by the transmitted signaling current to effect the movement of the relay G_1 to its energized position. The closing of the contacts 13 of the relay G_1 completes a circuit for the green lamp G and also for the white lamp W, and the closing of the contacts 11 of the relay G_1 prepares a circuit for the holding winding G_2 so that it becomes energized to maintain the relay G_1 in its energized position after the selector switches A and A_1 have rotated to the other positions in which the circuit of the operating winding G_1 is interrupted. The simultaneous lighting of the green and white lamps informs the dispatcher that the circuit breaker has moved to its open position. By moving the disagreement key DK to its other position, the dispatcher can extinguish the white lamp W.

Since both of the holding windings R_2 and G_2 are prevented from being energized when the selector switches A and A_1 are in a position to transmit a signaling current to either of the operating windings G_1 and R_1 , it is evident that if for any reason the signaling current is not transmitted when the selector switches are in that position or the signaling current fails to effect the operation of a relay to its energized position, neither the red lamp R nor the green lamp G is lighted. Consequently, there can be no incorrect lighting of the signal lamps.

While I have, in accordance with the patent statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure by Letters Patent of the United States is:

1. In combination, two stations, two conductors interconnecting said stations, a movable device at one of said stations having two positions, two relays at the other station, each relay having an operating winding and a holding winding, a source of current, means controlled by each relay when in its energized position for connecting the holding winding thereof across said source, means for impressing across said conductors a voltage of a polarity dependent upon the position of said device, and means for effecting simultaneously the deenergization of the holding winding of each energized relay and the connection of said operating windings across said conductors in such a manner that current flows through one of said operating windings only when a voltage of a predetermined polarity is impressed across said conductors and current flows through the other of said operating windings only when a voltage of the opposite polarity is impressed across said conductors.

2. In combination, two stations, two conductors interconnecting said stations, a movable device at one of said stations having two positions, two relays at the other station, each relay having an operating winding and a holding winding, a source of current, an impedance, means controlled by each relay when in its energized position for connecting the holding winding

thereof and said impedance in series across said source, two half wave rectifiers, means for impressing across said conductors a voltage of a polarity dependent upon the position of said device, means for effecting simultaneously the completion of a shunt circuit around the holding winding of each energized relay and the connection of one of said operating windings and one of said rectifiers in series across said conductors so that current flows through said one of said operating windings only when a voltage of a predetermined polarity is impressed across said conductors and the connection of the other of said operating windings and the other of said rectifiers in series across said conductors so that current flows through said other of said operating windings only when a voltage of the opposite polarity is impressed across said conductors, and signaling means selectively controlled by said relays.

3. In combination, two stations, two conductors interconnecting said stations, a movable device at one of said stations having two positions, two relays at the other station, each relay having an operating winding and a holding winding, a source of current, an impedance, means controlled by each relay when in its energized position for connecting the holding winding thereof and said impedance in series across said source, and synchronously-operated multiple-position switching means at the two stations for effecting simultaneously when in predetermined corresponding positions the connection of the operating windings of said relays across said conductors in such a manner that current flows through one of said operating windings only when a voltage of a predetermined polarity is impressed across said conductors and current flows through the other of said operating windings only when a voltage of the opposite polarity is impressed across said conductors and the completion of a shunt circuit around the holding winding of whichever relay has its operating winding energized while said switching means are in said predetermined corresponding positions and the impression across said conductors of a voltage of a polarity dependent upon the position of said device.

4. In combination, two stations, two conductors interconnecting said stations, a two-position device at one of said stations, two relays at the other station, each relay having an operating winding and a holding winding, a source of current, means controlled by each relay when in its energized position for connecting the holding winding thereof across said source, synchronously-operated multiple-position selector switches at the two stations, and means controlled by said switches when in predetermined corresponding positions for effecting simultaneously the connection of said operating windings across said conductors in such a manner that a predetermined one of said operating winding is energized only when a voltage of a predetermined polarity is impressed across said conductors and the other operating winding is energized only when a voltage of the opposite polarity is impressed across said conductors and the deenergization of each energized holding winding and the connection across said conductors of a voltage of a polarity dependent upon the position of said device.
5. In combination, a circuit, two relays, each relay having an operating winding and a holding winding, means for impressing voltages of opposite polarities across said circuit, a source of current, an impedance, means responsive to the energization of an operating winding for connecting the associated holding winding and said impedance in series across said source, and switching means for effecting simultaneously the connection of said operating windings to said circuit in such a manner that current flows through one of said operating windings only when a voltage of one polarity is impressed across said circuit and current flows through the other of said operating windings only when a voltage of the opposite polarity is impressed across said circuit and the completion of a shunt circuit around the holding winding of an energized relay while the associated operating winding is connected to said circuit.
